UNITED STATES PATENT OFFICE

SAMUEL FERGUSON, OF SCHENECTADY, NEW YORK, ASSIGNOR TO GENERAL ELECTRIC COMPANY, A CORPORATION OF NEW YORK.

PROTECTION OF SECONDARY CIRCUITS.

No. 851,739.

Specification of Letters Patent.

Patented April 30, 1907.

Application filed September 9, 1904. Serial No. 223,823.

To all whom it may concern:

Be it known that I, SAMUEL FERGUSON, a citizen of the United States, residing at Schenectady, county of Schenectady, State of New York, have invented certain new and useful Improvements in the Protection of Secondary Circuits, of which the following is a specification.

This invention relates to means for protecting electrical apparatus from abnormal high voltage currents.

While my invention is readily applicable to many cases, it is shown in the drawing, forming a part of this specification, as applied to an alternating current distributing system in which current at high potential is transmitted to a point near the place of consumption and there transformed or converted into current of suitable working pressure. In such systems there is always more or less danger of an accidental connection between the high potential conductors of the transformer coils and the low potential circuits thereby raising the secondary net work to the potential of the high voltage conductors and consequently endangering life and apparatus along the secondary net work.

In the drawings Figure 1 shows diagrammatically the high potential windings of three transformers connected in delta to high potential distributing mains; it also shows the secondaries of these same transformers connected to low voltage service mains; Fig. 2 is a sectional elevation of an improved form of film cut-out used in the ground connections of the secondary circuit.

In Fig. 1, 1, 2 and 3 represent respectively the primaries of three step-down transformers connected in delta to the high voltage mains 4, 5 and 6. These high voltage mains are provided respectively with ground connections 10, 11 and 12, each of these ground connections being provided with means for impeding the flow of current. In the drawing, I have shown these impedance devices 13, 14 and 15 as consisting of non-inductive resistances, but it is obvious that reactances could be used for this purpose if such an arrangement appeared desirable. The resistance of the ground connections is sufficiently high to prevent the loss of a large per cent. of the current supplied to the transformers, so that the loss of current in this way is comparatively small.

Secondaries 1', 2' and 3', corresponding respectively to the primaries 1, 2 and 3, are connected in delta to the low voltage distributing conductors 7, 8 and 9. Each of these conductors is connected to ground through a film cut-out of the type shown in Fig. 2. This cut-out comprises a metal block 19 preferably of brass having a screw-threaded chamber in its upper side into which fits a hollow inverted cup 20 of fiber or other suitable insulating material. The interior of the cup 20 is filled with a conducting liquid 21 preferably mercury which is insulated from the brass cup 19 by a thin layer of insulating material 22 such as paper or mica. This film of insulating material is held firmly between the block 19 and the insulating cup 20 and serves to prevent electrical contact of the mercury with the block 19. A small depression 23 may be made in the block 19 immediately below the insulating film into which is introduced a globule of mercury to insure a better contact between the main body of mercury and the block 19 when the paper film breaks down in the manner hereinafter described. A binding screw 24 passes through the top of the insulating cup 20 and provides a means for making electrical contact with the mercury 21. Binding screw 25 serves to connect the metal block 19 to the ground wire.

If from any cause the secondary circuit is subjected to high voltage as for instance by failure of the insulation between the primary 1 and the corresponding secondary 1', the high voltage current will pass to ground through one or more of the film cut-outs 16, 17 and 18 and back to the primary circuit through one or more of the impedance devices 13, 14 and 15. The passage of current through the film cut-outs will be effected by the destruction of the films by the high voltage current thereby forming a permanent connection between the mercury 21 and the metal block 19. As the secondary winding 1', 2' and 3' offer a comparatively small reactance to the high voltage current the passage to ground from the secondary conductors will not be confined to any one film cut-out, but will in general take place through all three. Each of the coils 1', 2' and 3' will then be permanently short-circuited through the ground, the consequence being an excessive rush of current in the primary coils of

the transformers and the opening of the fuses or other protective devices in the high potential mains thereby relieving the secondary circuit from all danger of the high potential voltage.

5. In the film cut-out shown in Fig. 2, the insulating film 22 is not exposed to the atmosphere, and consequently is not subjected to deterioration from moisture or other atmospheric conditions, and as the mechanical strain on the paper is dependent entirely on the weight of the column of mercury 21, great uniformity in the operation of the cut-outs is secured.

15. What I claim as new and desire to secure by Letters Patent of the United States, is,—

1. In an electrical distributing system, the combination of high potential conductors, a permanent ground connection of high impedance for each of said conductors, low potential conductors, and automatic means for permanently connecting said low potential conductors to ground when primary high potential occurs on said low potential conductors.

2. In an electrical distributing system, the combination of high potential mains, transformers having their primaries connected in delta between said mains, a permanent ground connection of high impedance for each corner of said delta, secondaries for said transformers, and means for automatically connecting said secondaries to ground when primary high potential occurs on said secondaries.

3. In an electrical distributing system, the combination of high potential mains, transformers having their primaries connected in delta between said mains, a permanent ground connection of high impedance for each corner of said delta, secondaries for said transformers connected in delta, and means for connecting said secondaries to ground comprising a mercury electrode and a metallic

electrode separated by a thin insulating me- 45 dium.

4. An automatic circuit closing device comprising two mercury conductors separated by a thin insulating member, and means for connecting said conductors to an 50 electrical circuit.

5. An automatic circuit closing device comprising two liquid conductors separated by an insulating film, one of said conductors consisting of mercury, and means for connecting said mercury to an electrical circuit. 55

6. A circuit closing device comprising a metallic conductor, an insulating cup secured to said conductor, a thin layer of insulating material clamped between said cup and conductor, and a body of mercury normally supported by said thin layer of insulating material and insulated from said metallic conductor. 60

7. A circuit closing device comprising a metallic block, an inverted cup of insulating material carried thereby and supporting a column of mercury, a metal conductor passing through said cup of insulating material and contacting with said mercury, a thin 70 layer of insulating material between said mercury and said block, and means for connecting said mercury to an electrical circuit.

8. A film cut-out comprising a metallic block having a chamber in its top, an inverted cup of insulating material screwed into said chamber, a body of mercury in said insulating cup, a paper film supporting said mercury and normally separating it from said metallic block, and an electrical connection 75 for said mercury through said insulating cup.

In witness whereof, I have hereunto set my hand this eighth day of September, 1904.

SAMUEL FERGUSON.
